Primary Examiner — Susan Bennett Hattan(74) *Attorney, Agent, or Firm* — Womble Carlyle Sandridge & Rice, LLP(57) **CLAIM**

The ornamental design for a tray assembly for a dispensing container, as shown and described.

DESCRIPTION

FIG. 1 is a top, front perspective view of a tray assembly for a dispensing container according to the present design, the tray assembly having a translucent cover with multiple cut-out portions formed therein;

FIG. 2 is a top, rear perspective view of the tray assembly for a dispensing container illustrated in FIG. 1;

FIG. 3 is a top plan view of the tray assembly for a dispensing container illustrated in FIG. 1;

FIG. 4 is an exploded front view of the tray assembly for a dispensing container illustrated in FIG. 1; and,

FIG. 5 is an exploded rear view of the tray assembly for a dispensing container illustrated in FIG. 1.

The broken lines shown herein depict environmental subject matter only and form no part of the claimed design.

1 Claim, 5 Drawing Sheets(56)
